UNITED STATES PATENT OFFICE.

FREDERICK W. DONNELLY AND WILLIAM J. SMITH, OF NEW YORK, N. Y.;
SAID SMITH ASSIGNOR TO THOMAS DONNELLY; THOMAS DONNELLY
ADMINISTRATOR OF FREDERICK W. DONNELLY, DECEASED.

SIGN.

SPECIFICATION forming part of Letters Patent No. 786,550, dated April 4, 1905.

Application filed April 4, 1904. Serial No. 201,609.

To all whom it may concern:

Be it known that we, FREDERICK W. DONNELLY, a resident of 71 East Fifty-ninth street, and WILLIAM J. SMITH, a resident of 217 West 5 One Hundred and Forty-second street, New York, in the county of New York and State of New York, citizens of the United States, have invented certain new and useful Improvements in Signs, of which the following 10 is a specification.

Our invention relates to signs and symbols capable of illumination from within or behind.

The objects of the invention are to provide a sign capable of illumination by night and 15 which can be readily seen and understood by day and to so locate the letters on the sign-board or other support that the sign can be read with both facility and clearness when approached at an angle or when directly approached.

20 A further object of the invention is to provide a means whereby a sign of the character described may be constructed rapidly and in a simple, durable, and economic manner, and 25 so that any manner of light may be employed.

We attain these objects in the construction illustrated in the drawings and described and claimed hereinafter.

Like characters of reference refer to like 30 parts throughout the respective views.

Figure 1 is a front elevation of a portion of a sign illustrating the application thereto of a single letter. Fig. 2 is a horizontal section taken practically on the line 2 2 of Fig. 1. 35 Fig. 3 is a section similar to that shown in Fig. 2, illustrating the application of a letter having a slightly-different front face from that shown in Fig. 2. Fig. 4 is a front elevation of a portion of a sign carrying out 40 the invention and illustrating a construction which admits of the letters being placed directly upon the front face of the sign board or support. Fig. 5 is a horizontal section taken practically on line 5 5 of Fig. 4. Fig. 45 6 is an elevation showing another form of letter in which the border or frame is omitted and the interior field is shown spaced from the interior outline of the letter. Fig. 7 is a

cross-section of Fig. 6 on the line 3 3. Fig. 8 shows a modification in the shape of our 50 border or frame and the letter. Fig. 9 is a cross-section of Fig. 8 on the line 4 4. Fig. 10 shows another form of letter, the interior field being spaced from the walls of the letter. Fig. 11 is a cross-section of Fig. 10 on the 55 line 5 5.

A represents a sign-board or other support in connection with which letters or other symbols B are to be employed and displayed. An opening 10 is made in the sign-board or support for displaying each letter or character making up the sign. Each opening 10 is of greater area than the area of the letter it is adapted to receive, it being understood that the aforesaid openings are of the same 60 contour as the symbols adapted to be placed in them, so that a space is provided between a symbol and the inner wall of the opening in which the symbol is placed, through which space the rays of light from a means of illumination located at the back of the sign-board may pass outward, thus providing an illuminated outline of the whole symbol which is within the opening, which symbol is especially designed to be read by day. The letters are held in suspension in the aforesaid 65 openings 10 in any approved manner—as, for example, by metal plates 11, (shown in Figs. 1, 2, 3, 6, 7, 8, and 9,) which plates are secured to the back faces of the letters, extending across the spaces between the letters and the inner walls of the openings in which the letters are held, or by wires or other securing means. The ends of the said plates or wires 11 are secured in any suitable or approved manner to the sign board or support 70 A. Preferably the said attaching or fastening plates 11 are made as thin as possible where they cross the spaces between the walls of the openings and the adjacent margins of 75 the letters, as is clearly shown at 12 in Figs. 1, 2, 3, 6, 7, 8, and 9.

The letters B may be made of any suitable or approved material. Preferably an opaque material is employed—for example, wood— 80 and the letters are made of such thickness that

they extend a suitable distance beyond the front face of the sign-board or support A. In Fig. 2 the letters are illustrated as having a flat outer or front face 13, and their margins at the front face are chamfered, (though this is not necessary,) as is shown at 14 in said Fig. 2. In Fig. 3 the letters B are illustrated as being provided with convexed outer faces 15, and in connection with the support or sign-board A, no matter what the character of the letter may be, we preferably employ a border 16, which is secured to the face of the sign-board or support A, and the inner face of the border is preferably flush with or forms the walls of the opening 10, in which a letter is placed. The front or outer face of the said border 16 is inclined from the outer face of the sign-board or support A upwardly in direction of the opening, which the border may 15 surround, or it may be a thin strip, as appears in Figs. 8 and 9. The border 16 need not extend outward as far as the outer face of the letter in the opening surrounded by the border. In fact, the outer face of the border at 20 its thickest portion preferably terminates short of the chamfered edges 14 of the flat letter shown in Fig. 2 and short of the convexed outer face 15 of the letter shown in Fig. 3. As will be seen on reference to Figs. 6 and 7, 25 we may omit the border or frame 16 entirely, thus leaving merely a space 10 between the letter B and the edges of the field A, the function of the border not being essential, but advisable in the embodiment of our invention, 30 the essence of which is the space or aperture outlined symbol and the securing a symbol of smaller size in the opening in the field. Under such construction it is obvious that the letter may be read clearly when the sign is approached at an angle and need not necessarily 35 be approached directly, as the light will indicate the outline of a letter by night and the forward edges of the letter will give its outline by day, as the sides and ends or marginal 40 portions of the letters are preferably painted white, so as to accurately define the outline of the letters by day and to facilitate the light penetrating the space surrounding the letters and render visible the outlines of the letters 45 by night.

In Fig. 4 the same principle is carried out as has been illustrated in the construction shown in Figs. 1, 2, and 3; but the letters B are cemented or otherwise secured directly 50 to the outer face of the sign-board or support A; but previously to placing the letters on the board a series of apertures 17 is produced in the sign-board or support, placed as closely as possible consistent with strength, and the 55 arrangement of the apertures corresponds to the outlines of the letters to be placed practically over them. When a letter is placed in position on a sign-board or support A thus apertured, a portion of the margin of 60 the letter extends over the apertures 17, as is

best shown in Fig. 5, and the border 16, heretofore described, which is also, preferably, employed and is attached to the outer face of the sign-board or support, also extends partially over the apertures 17, so that a space 70 is provided between the border 16 and the margin of a letter which it surrounds, which space corresponds to the space shown in the construction illustrated in the other views. This space is rendered more or less continuous 75 for the passage of light, the passage of light being interrupted only by the narrow partitions between the apertures, so that practically the same result is obtained when a letter is applied in the manner shown in Figs. 4 and 80 5 as when a suspended letter is used, as is indicated in Figs. 1, 2, and 3.

It will be understood that we do not limit ourselves to any special form of letter or figure, but include any symbol or representation, 85 nor do we limit ourselves to any means of securing the letter to the field, as by plates, as we may and sometimes do use wires soldered or otherwise secured to the symbol and field. Equally we do not limit ourselves to a receptacle, though we often preferably place the illuminant in one, one or more of the faces of which constitute the face or field of the sign, and where we use the singular, as "a symbol" or "an opening," we also include 95 the plural, as "symbols" or "openings," the latter being a difference only in number or quantity and not affecting the principle of our invention, which applies equally to one or more. 100

Where we have used the words "lateral sectional area" in the claims we mean the area of a section taken in a plane parallel with the front face of the sign.

Having thus described our invention, we 105 claim as new and desire to secure by Letters Patent—

1. In a sign, a support having openings, letters carried by the said support within said openings, the sides of the letters being parallel with the walls of the opening and spaced apart therefrom, and borders carried by the said support along the outer marginal portions of the said openings, the openings and borders forming as it were margins for the 110 letters.

2. In a sign, a board or support having openings in the form of letters extending through said board or support, the walls of said openings being at right angles to the rear face of 120 the support, borders secured to the outer face of the board or support around said openings, the inner walls of the borders being in alignment with the walls of the openings and forming continuations thereof, and letters corresponding in shape to the form of the openings but of less dimensions and carried by the board or support within said openings, the edge walls of the letters being parallel 125 with the walls of the openings, the rear faces 130

of the letters being flush with the rear face of the support and the front faces of the letters projecting forwardly in advance of the front face of the support and also of the borders surrounding the openings in the support.

3. In a sign, a board or support having an opening therein corresponding to the form of a given letter, the walls of the opening being at a right angle to the face of the support, a letter conforming to the opening and suspended therein, with its rear face flush with the rear face of the support, the letter being of less area than the area of the opening, thereby providing a space between the margins of the letters proper and the walls of the opening, the edge walls of the letter being parallel with the adjacent walls of the opening, and sustaining devices for the letter as set forth.

4. In a sign, a board or support having an opening therein of corresponding shape to a given letter, a letter fitted to the said opening, yet of less dimensions than said opening, whereby a space is provided between the letter and the walls of the opening, the letter projecting outward beyond the front face of the said board or support, means for holding the said letter in suspension in the said opening, and a border extending around the opening at the outer face of the board or support, which border has its outer or front face inclined outward from the board or support in direction of the said letter, the outer face of the letter extending beyond the edge portion of the border adjacent to the space surrounding the letter, as described.

5. In a sign, a board or support having an opening therein corresponding in shape to a given letter, a letter fitted to the said opening, yet of less dimensions than said opening, whereby a space is provided between the letter and the walls of the opening, the letter projecting outward beyond the front face of the said board or support, means for holding the said letter in suspension in the said opening, and a border extending around the opening at the outer face of the board or support, which border has its outer or front face inclined outward from the board or support in

direction of the said letter, the outer face of the letter extending beyond the edge portion 50 of the border adjacent to the space surrounding the letter, the said letter being provided with chamfered edges at its front face, and provided with a marginal coating of a white material, for the purpose set forth.

6. In a sign, a support having openings, letters carried by the said support, the sides of the letters being parallel with the sides of the openings, and borders carried by said support, said borders surrounding the letters and 60 spaced apart therefrom on all sides to form an unbroken space between said letters and their borders, the letters projecting outwardly beyond the borders.

7. In a sign, a support adapted to have a 65 light at one side thereof, a letter carried upon the support, and a frame surrounding said letter and spaced therefrom, a part of said support being cut away to permit light to shine through the support between said frame and 70 said letter.

8. In a sign, a field having an opening of substantially the outlines of a symbol, and a symbol whose lateral sectional area is everywhere less than the area of the opening secured 75 therein, and spaced at all points apart from the walls of the opening, substantially as described.

9. In a sign, a field having an opening of substantially the outlines of a symbol, a symbol whose lateral sectional area is everywhere less than the area of the opening secured there- 80 in, and spaced at all points apart from the walls of the opening, the interior field of said symbol being smaller than the interior out- 85 line of the symbol and spaced therefrom, substantially as described.

Signed at New York, in the county of New York and State of New York, this 1st day of April, A. D. 1904.

FREDERICK W. DONNELLY.
WILLIAM J. SMITH.
